[57] CLAIM

The ornamental design for a faucet handle, as shown and described.

DESCRIPTION

FIG. 1 is a perspective view of a faucet handle showing our new design;

FIG. 2 is another perspective view thereof;

FIG. 3 is a top plan view thereof; and

FIG. 4 is a side elevational view thereof, the other sides being the same as the side shown.

The broken line representation of a lavatory faucet in FIG. 1 and of a single valve in FIG. 2 is for purposes of illustration only.

Fig. 2.

Fig. 1.

Fig. 3.

Fig. 4.
